United States Patent Office.

GUSTAVUS HAMEL, OF DE SOTO, MISSOURI.

Letters Patent No. 104,144, dated June 14, 1870.

IMPROVED WASHING-MACHINE.

The Schedule referred to in these Letters Patent and making part of the same.

To all whom it may concern:

Be it known that I, GUSTAVUS HAMEL, of De Soto, in the county of Jefferson and State of Missouri, have invented a new and useful Improvement in Washing-Machines; and I do hereby declare that the following is a full, clear, and exact description thereof, which will enable others skilled in the art to make and use the same, reference being had to the accompanying drawing, forming a part of this specification, in which—

Figure 1 is a detail sectional view of my improved washing-machine.

Figure 2 is a detail view of the revolving wash-boards.

Similar letters of reference indicate corresponding parts.

My invention has for its object to furnish an improved washing-machine, simple in construction, easily operated, and effective in operation, washing small and large articles with equal facility and thoroughness; and

It consists in the construction and combination of the various parts of the machine, as hereinafter more fully described.

A is the box or tub of the machine, which is made somewhat hopper-shaped, and which is supported upon legs, B, of such a length as to raise the machine to a convenient height.

C is the cover, which is made curved or arched, and the rear edge of which is hinged to the rear part of the box or tub A.

To the forward part of one end of the cover C is attached a handle, D, for convenience in raising and lowering the said cover.

E is a notched catch-bar, the upper end of which is pivoted to one end of the cover C, so as to catch upon a pin, F, attached to the end of the box or tub A, and hold the cover C raised to any desired extent.

G is a wash-board, formed by passing brass spring wires through bolts in the ends of rounds or bars, rubber blocks being placed upon the said wires between the said rounds, to keep the rounds at the proper distance apart.

The lower round of the wash-board G rests upon the bottom of the tub or box A, and the ends of the upper round rest in notches in brackets, a', attached to the box A, in the upper part of its forward corners, as shown in fig. 1, where it is secured in place by the inclined board H, which rests upon the upper ends of the brackets a', and is kept in place by pins placed in holes passing in an inclined direction through the ends of the said board H, and into the end boards of the tub A.

The forward edge of the cover C rests upon the upper side of the board H.

I is a board or plank, having journals formed upon or attached to the middle parts of its ends, which journals pass through and work in holes in the ends of the tub or box A.

J are wash or rubber-boards, constructed of spring wire, rubber blocks, and rounds, in exactly the manner in which the wash-board G is formed.

The wash-boards J are secured to the edges of the board I by coiling the ends of the spring wires of said wash-boards around pins formed by notching the end edges of said board close to its side edges, as shown in fig. 2.

With the middle part of the outer rounds of the wash-boards J are connected the ends of the pieces of webbing, K, the inner ends of which are attached to and wound around a small roller, L, pivoted in a slot in the middle part of the board I, so that, by turning the roller L in one or the other direction, the said webbing K may be wound upon or unwound from the said roller L.

The roller L is turned to wind and unwind the webbing, and thus regulate the wash-boards J, by means of pins, M, or short levers passed through holes in the said rollers, and is held in position by the said pins M, resting against the said board I, as shown in figs. 1 and 2.

To the projecting end of one of the journals of the board I is attached a fly-wheel, N, to give steadiness to the movement of the machine. To the projecting end of the other journal of the board I is attached a crank, O, by means of which the machine is operated.

To one of the journals of the board I is attached a ratchet-wheel, P, upon the teeth of which rests the pawl Q, which is pivoted to the end of the tub A, and which thus prevents the machine from being turned backward.

The ends of the rounds of the wash-boards I may have pieces of tape or webbing attached to them to prevent the clothes from being caught upon the ends of the said shaft and being torn.

In using the machine, the clothes are raised by the wash-board J, and are carried up along and rubbed against the wash-board G. The clothes are released by the wash-board J before reaching the inclined board H, and are allowed to drop back into the water to be again operated upon by the next wash-board, J, the water being all the time violently agitated.

In the case of very large articles the wash-board G may be removed, and the article washed by the agitation of the water alone.

Having thus described my invention,

What I claim as new, and desire to secure by Letters Patent, is—

1. Forming wash-boards for washing by passing spring wires through the ends of rounds, and through

rubber blocks, interposed between the said rounds, substantially as herein shown and described.

2. The combination of the revolving board or plank I, wash-boards J, webbing K, roller L, and pin or pins M, with each other, substantially as herein shown and described, and for the purposes set forth.

3. The combination of the detachable wash-board G, with the tub or box A, and with the revolving wash-boards I J K L M, substantially as herein shown and described and for the purpose set forth.

4. An improved washing-machine, formed by the

combination of the box or tub A B C, detachable wash-board G, detachable inclined board H, revolving wash-boards I J K L M, fly-wheel N, crank O, ratchet-wheel P, and pawl Q, with each other, substantially as herein shown and described and for the purpose set forth.

GUSTAVUS HAMEL.
